UNITED STATES PATENT OFFICE.

HERBERT A. BEENK, OF CEDAR RAPIDS, IOWA.

TELEPHONE ATTACHMENT.

Application filed December 4, 1924. Serial No. 753,933.

To all whom it may concern:

Be it known that I, HERBERT A. BEENK, a citizen of the United States of America, residing at Cedar Rapids, in the county of Linn and State of Iowa, have invented certain new and useful Improvements in Telephone Attachments, of which the following is a specification.

My invention relates to improvements in supports for pads and the like and more especially to supports of this character which are especially adapted for attachment to telephones, although not necessarily restricted to this location.

15 An important object of my invention is to provide a device of the above mentioned character which will serve as a support for advertising matter.

Another object of my invention is the provision of a device of this character which will combine with a pad supporting means, means to grasp a memorandum slip, and means for removably securing a pencil or the like.

25 Still another object of my invention is to provide a device of this character which will be of simple construction, easily installed, and strong and durable.

Other objects and advantages of my invention will be apparent during the course of the following description.

In the accompanying drawings, which form a part of this specification and wherein like numerals denote like or corresponding parts throughout the same;

Figure 1 is a perspective view of a telephone equipped with a device embodying my invention,

Figure 2 is a detail of the blank from which the device is formed,

Figure 3 is a plan view of the complete attachment, and,

Figure 4 is a central longitudinal section through the same.

45 In the drawings, wherein for the purpose of illustration is shown a preferred embodiment of my invention, the numeral 10 designates a blank of any suitable material such as metal, celluloid, or the like, provided with a contracted neck portion 11 between its ends adapted to be bent upon itself at its central portion to form a cylindrical socket 12 for a pencil 13 or the like. An auxiliary clip 14 is struck up from the neck portion and is adapted to resiliently engage the pencil.

The portion 15 of the blank below the neck portion 11 is adapted to be bent upwardly so as to lie flush against the surface of the back portion 16, the portion 15 terminating a substantial distance short of the end of the back portion 16, and being provided with a guiding clip 17 at its end.

60 The sections 15 and 16 are provided with corresponding openings 18 spaced from the ends of the section 15, through which the mouthpiece 19 of a telephone 20 is adapted to extend. The shoulder 21 of the mouthpiece clamps the sections 15 and 16 together so that the upper end of the section 15 is 70 normally held in engagement with the section 16, but it may be moved from engagement therewith, against the tension of the section due to the clamping action of the mouthpiece 19.

75 Clips 22 are struck up from the section 15 to receive advertisements 23, which are arranged in plain view above and below the telephone mouthpiece. The back section 16 is provided with clips 24 struck therefrom, 80 which receive the back of the pad 25 which is adapted to be slipped over the top of the section 16, as shown in Figures 1 and 4.

85 Memorandum slips, may be slipped between the sections and clamped in place in plain view as at 26. If desired the pad may be inserted between the section instead of over the end of the back section 16. While I have shown the device applied to a telephone, it may be secured to a wall or the like 90 by means of the openings 27, if desired.

95 It will be seen that I have provided a device which can be easily and cheaply constructed of a single piece of material and which has provision for supporting a pad, pencil, advertisements, and memorandum slips, cards or the like.

100 While I have shown and described the preferred embodiment of my invention, it is to be understood that various changes in the size, shape, and arrangement of parts may be resorted to without departing from the spirit of my invention or the scope of the subjoined claims.

Having described my invention what I 105 claim and desire to protect by Letters Patent is:

1. In a telephone attachment, a blank adapted to be folded upon itself to form two superimposed sections, the upper of the 110 sections terminating a substantial distance short of the lower of the sections, cor-

responding openings spaced from the ends of the sections to receive the mouthpiece of the telephone which is adapted to clamp the sections together to form a card holding clasp, a pencil clasp formed integrally with the sections, means on said lower section to receive a pad, and clips formed integrally with the sections.

2. In a telephone attachment, a blank generally rectangular in formation and provided intermediate its ends with a reduced neck portion, and adapted to be folded upon itself to form two superimposed sections, said fold being arranged intermediate the ends of the neck portion so as to form a

cylindrical, pencil receiving compartment, the cylindrical portion having a clip struck therefrom and adapted to clasp the pencil, the upper of the sections terminating short of the lower of the sections, the sections being provided with corresponding openings spaced from the ends of the sections and adapted to receive the mouthpiece of the telephone which is adapted to clamp the sections together, whereby said sections form a card holding clasp.

In testimony whereof I affix my signature.

HERBERT A. BEENK.
